UNITED STATES PATENT OFFICE.

EDGAR F. BOSWORTH, OF ATTLEBOROUGH, MASSACHUSETTS, ASSIGNOR TO
DAGGETT & CLAP, OF SAME PLACE.

BUTTON.

SPECIFICATION forming part of Letters Patent No. 308,300, dated November 18, 1884.

Application filed June 10, 1884. (No model.)

To all whom it may concern:

Be it known that I, EDGAR F. BOSWORTH, of Attleborough, in the county of Bristol and State of Massachusetts, have invented a new 5 and useful Improvement in Buttons; and I do hereby declare that the following is a full, clear, and exact description of the same.

My invention is an improved button adapted for use as a sleeve or collar button and like 10 purpose. It is of that class in which the shoe is pivoted upon the post, and is adapted to turn aside from the center of the shoe when the latter is turned for introducing it into or removing from the button-hole.

15 The invention consists in details of construction, hereinafter described, the objects of which are to provide a securely-hinged connection between the post and the shoe with economy in the manufacture.

20 In the accompanying drawings, Figure 1 shows the post and shoe in perspective. Fig. 2 is a perspective view of the post and the bearing and spring plates. Fig. 3 shows a transverse section on post and shoe, taken 25 centrally through both.

The post is a flat bar tapering preferably from the button to the shoe, and may be struck out of sheet metal to the proper thickness. The smaller end is turned aside at right angles to the main part, forming an offset, *a*, 30 which is provided with two journal-pins, *11*. These may be formed when the post is struck out, and the offset afterward formed by bending the end. I prefer to use a bottom plate 35 consisting of a disk of thin elastic metal, *b*, Fig. 2. On this I place a disk, *c*, Fig. 3, which is made a little thicker, preferably, than the other, and is provided with an opening cut through the metal, adapted exactly to receive 40 the offset with its pins or journals *11*, and when these are set into the opening accurately the post stands vertically in the center of the disk *c*. Above this I place another disk, *d*, of thin elastic sheet metal, having an opening, 45 *2*, and slits cut from one end of the opening, which allows the metal on the sides of the open-

ing to spring up when the post is turned. This is placed over the plate *c*, with a longer side of the opening lying across the pins or journals of the post, so that these pins extend 50 under the elastic sides. Over these three plates a cap, *e*, is placed, and its edges are spun or pressed down, so as to hold them closely together. The offsets of the post and its journals are lodged in the cavity of the disk *c*, and the journals are held securely between the upper and lower plates. These journals are square in cross-section, and when the post is turned their corners slowly spread the spring-disk in turning, the plates pressing against 55 the sides of the journals, when the post is either at right angles or parallel with the face of the shoe, and thus in those positions the shoe is held with sufficient force.

The parts described are cut out of sheet 60 metal, and the opening, when formed, is strong and secure in its action.

As the journals are on one side of the center, the shoe turns on this center, and is thus more easily inserted through or removed from 70 the button-hole.

I am aware that a post formed with journals aside from the center and clamped beneath a spring plate is not new.

I claim as my invention—
75 The combination of the post formed with an offset and journals *11*, a disk, *c*, provided with the opening for the right-angular offset with its journals, the T-shaped opening for the journals being on one side of the center, a disk, *d*, having an opening and slits, as described, placed over the disk *c*, a suitable disk below the disk *c*, and a suitable shell for the cover of the shoe, and holding the parts together, all substantially as described.

80 In testimony whereof I have signed my name to this specification in the presence of two subscribing witnesses.

EDGAR F. BOSWORTH.
